UNITED STATES PATENT OFFICE.

CHARLES C. MOORE, OF NEW YORK, N. Y.

DESIGN FOR A NOVELTY CAT.

Application filed April 7, 1926. Serial No. 17,209. Term of patent 7 years.

To all whom it may concern:

Be it known that I, CHARLES C. MOORE, a citizen of the United States, and a resident of the city of New York, borough of Manhattan, in the county and State of New York, have invented a new, original, and ornamental Design for a Novelty Cat, of which the following is a specification.

Reference is to be had to the accompanying drawing, in which—

Figure 1 is a perspective view of a novelty cat showing my new design as it appears from one side and front, and

I claim:

The ornamental design for a novelty cat as shown.

CHARLES C. MOORE.
